UNITED STATES PATENT OFFICE.

BENJAMIN M. WEINBERGER, OF MILWAUKEE, WISCONSIN.

INDICATING MEANS.

Application filed March 3, 1921. Serial No. 449,286.

To all whom it may concern:

Be it known that I, BENJAMIN M. WEINBERGER, a citizen of the United States, and resident of Milwaukee, in the county of Milwaukee and State of Wisconsin, have invented new and useful Improvements in Indicating Means, of which the following is a description, reference being had to the accompanying drawings which are a part of this specification.

This invention relates to certain new and useful improvements in indicating means and refers more particularly to means of this character adapted to be applied to guest rooms in a hotel or any similar establishment.

At the present time, it is impossible for the chamber maid to ascertain whether a guest is in the room without trying to enter with a pass key, which is annoying and disturbing to the guest and also consumes a large part of the maid's time. Some hotels have sought to solve this perplexing problem by the crude and expensive method of placing a towel on the door knob of each room early in the morning and from time to time the maid passes through the hall and whenever a towel is missing she assumes the guest is out and the room ready for her services.

Hence with the above and other objections in mind to the present system of running an establishment of the hotel class, it is one of the objects of this invention to provide means mounted on the outside of each guest room door and operable by the turning of the lock bar actuating bolt to indicate when the door is locked or unlocked, from the inside, and consequently whether the room is occupied.

My invention has for another object to provide means independent of the lock actuated indicating means and which is set by the maid after the room has been prepared to indicate that the same is in condition to receive a guest.

A further object of this invention is to provide the turn bolt actuated indicating means and the maid actuated means, which latter means is automatically moved to non-indicating position upon the locking of the door from the inside.

A still further object of this invention is to provide a device of the class described which will not, in any manner, mar the appearance of a door, which is easily and

quickly securable to the standard type of hotel door in which the means for locking the door from the inside consist of a slide bar and a turn bolt therefor, or which may readily be applied to door locks at the time of their manufacture.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a front view of an indicator embodying my invention, illustrating the parts in the position they occupy when the room is made up and prepared for a guest;

Figure 2 is a view similar to Figure 1 illustrating the indicator showing that the room is occupied;

Figure 3 is a view similar to Figure 2 illustrating the indicator as showing that the room is unoccupied and ready for the maid's attention;

Figure 4 is a sectional view taken through Figure 1 on the line 4-4;

Figure 5 is a sectional view taken through Figure 2 on the line 5-5; and

Figure 6 is a fragmentary sectional detail view taken through Figure 4 on the line 6-6.

Referring now more particularly to the accompanying drawing in which like numerals designate like parts throughout the several views:

The numeral 7 designates the door entering into a guest room and provided with a recess 8 in which is fixed a longitudinally slotted sleeve 9 having a locking bolt or sliding bar 10 mounted therein. The bar 10 has rack teeth 11 registering with the sleeve slot and which are engaged by a pinion 12 to slide the same into and out of a locking recess in the door jamb, not shown. The bar 10 is preferably operated to lock the door from the inside of the room only.

and is actuated by a turn bolt 13 having a squared shank 14 engageable with the gear 12 and a knob 15 for rotating the same. The squared shank portion 14 of bolt 13 extends beyond the gear 12 in order that no difficulty will be encountered in placing a standard lock on doors of varying thickness, and the present invention is preferably connected with the extended end of the squared shank 14.

The general lock construction of the door embodies a metal plate 16 secured to the exterior thereof and the plate 16 and door 7 are drilled or bored, as at 17, to register 15 with the opening 18 in which the gear 12 and bolt 13 are positioned. Projected into the bore 17 is a sleeve 19 having its inner end provided with opposed pairs of struck-in spaced portions 20 to provide means for 20 engaging opposed corners of the free end of the squared end 14 whereby said sleeve will be secured on said shank. The outer end of said sleeve extends slightly beyond the plate 16 and has secured thereon a disk 25 or plate 21, which disk has thereon suitable indicating means 22 and 23, representing preferably red and white, respectively. Completely enclosing the outer end of sleeve 19 and the disk 21 is a guard housing or 30 casing 24 consisting of a circular plate having its central portion raised or struck upwardly and secured to the door by fastening members 25, the raised portion of the housing having an opening 26 with which the indicating means 22 and 23 are adapted to register.

The connection between the bolt 13 and bar 10 is such that practically but a half turn of the knob 15 is necessary to lock and 40 unlock the door, and therefore the indicating means 22 and 23 are substantially diametrically opposite and when the bar 10 is in locked position, the indicating means 22 will be in register with opening 26, and 45 when in unlocked position indicating means 23 will be in register therewith. Slidably mounted on the extreme outer end of sleeve 19, intermediate disk 21 and the central wall of guard casing 24, is a plate 27 which is 50 movable to cover opening 26. The swinging of said plate 27 is limited by an out-struck portion 28 which projects through opening 26 and also provides means for moving the same to and from indicating position. 55 Said plate 27 is readily releasably secured in either of its two positions by an out-struck portion 29 which is engageable, when the plate is in position away from the opening in a notch or recess 30 in the housing 60 24 and which is engageable in a recess or notch portion 31 when said plate member 27 is closing the opening 26. The plate member 27 is normally yieldably urged to engage the inner wall of the guard housing 65 24 by a washer 32 confined between the disk

21 and the plate 16, as best shown in Figures 4 and 5.

The disk 21 has a projection or out-struck portion 33 on its outer face at the indicating means 22 so that, should the plate member 70 27 be closing the opening 26, a locking of the bar 10 by the guest will swing said disk from its position depicted in Figure 1 to the position depicted in Figure 2, said projection 33 engaging the end of member 27 75 adjacent its portion 28 and releasing the projection 29 from notch 31 and moving said member 27 until its projection 29 engages notch 30. While the door is locked from the inside, the plate 27 is secured 80 against movement by having its portion 28 confined between the adjacent end of opening 26 and projection 33, as depicted in Figures 2 and 5, said plate member being only 85 free to be moved to its position closing said opening when the bar member 10 is in unlocked position and the indicating means 23 in register with the opening.

The method of using this invention upon guest rooms of a hotel is substantially as 90 follows:

When a guest is in the room and has the door locked, the indicating means 22 will be visible through opening 26 and the maid will, at a glance, be able to ascertain that 95 the room is occupied and consequently will not annoy the guest by rattling the door in order to see if the same is locked. When the guest unlocks the bar 10 to leave the room, the indicating means 23 is moved to 100 register with the opening 26 and the maid can then readily ascertain that the room is unoccupied and ready for her to enter and perform the necessary duties. After the maid has placed the room in its proper condition, upon leaving she moves member 27 to its position depicted in Figure 1 to show that the room has been cleaned and is ready for a guest.

From the foregoing description taken in 110 connection with the accompanying drawing, it will be readily apparent to those skilled in the art to which an invention of this character appertains that I have provided means which will perform its functions in 115 a satisfactory manner, and which is so designed that all the parts thereof may be stamped from sheet metal, if desired, and which may be easily and quickly applied to doors at the time of their erection or to 120 doors now in use.

What I claim as my invention is:

1. In a device of the class described, the combination with door locking means including a turn bolt rotatable from the inner side of the door, of means on the outer side of the door and operable upon rotation of the turn bolt to indicate the position of the locking means, second indicating means movable to and from indicating position 125 130

independently of said turn bolt and adapted to cover the first mentioned indicating means, and means for readily releasably securing said second indicating means in either 5 of its two positions.

2. In a device of the class described, the combination with door locking means including a turn bolt rotatable from the inner side of the door, of means on the outer side of the door and operable upon rotation of the turn bolt to indicate the position of the locking means, and second indicating means movable to an indicating position covering the first mentioned indicating 10 means.

3. In a device of the class described, the combination with door locking means including a turn bolt rotatable from the inner side of the door, of means on the outer side of the door and operable upon rotation of the turn bolt to indicate the position of the locking means, second indicating means movable to an indicating position covering the first mentioned indicating means, and means carried 20 by said first mentioned indicating means for moving said second indicating means upon a rotation of said turn bolt to lock said locking means.

4. In a device of the class described, the combination with door locking means including a turn bolt rotatable from the inner side of the door, of means on the outer side of the door and operable upon rotation of the turn bolt to indicate the position of the locking 30 means and including a disk connected with and rotatable by said turn bolt and two indicating means on said disk, one indicating means being visually displayed when the bolt has been turned to lock said locking means and the other when said bolt has been turned to unlock said locking means, and means adapted to be moved to conceal the indicating means displayed when the locking means is in unlocked position.

5. In a device of the class described, the combination with door locking means including a turn bolt rotatable from the inner side of the door, of means on the outer side of the door and operable upon rotation of the turn bolt to indicate the position of the locking means and including a disk connected with and rotatable by said turn bolt and two indicating means on said disk, one indicating means being visually displayed when the bolt has been turned to lock said locking means and the other when said bolt has been turned to unlock said locking means, and independent indicating means movable to indicating position only when 40 said turn bolt has been turned to unlock said locking means.

6. In a device of the class described, the combination with door locking means including a turn bolt rotatable from the inner side of the door, of means on the outer side

of the door and operable upon rotation of the turn bolt to indicate the position of the locking means and including a disk connected with and rotatable by said turn bolt and two indicating means on said disk, one indicating means being visually displayed when the bolt has been turned to lock said locking means and the other when said bolt has been turned to unlock said locking means, independent indicating means movable to indicating position only when said turn bolt has been turned to unlock said locking means, and means for moving said independent indicating means from indicating position upon a turning of said bolt to lock the locking 70 means.

7. In a device of the class described, the combination with a door lock actuating bolt adapted to be rotated in one direction to lock the door and in a reverse direction to unlock 80 the door, of a sleeve having its inner end connected with the inner end of said bolt, a plate carried by the outer end of said sleeve and rotatable with said sleeve and bolt, said plate having two indicating means 85 thereon, a guard enclosing said plate and having an opening with which one of said plate carried indicating means registers when the bolt is in locked position and with which the other indicating means registers 90 when said bolt is in unlocked position, and a second plate movable to close said guard opening only when said bolt is in unlocked position.

8. In a device of the class described, the combination with a door lock actuating bolt adapted to be rotated in one direction to lock the door and in a reverse direction to unlock the door, of a sleeve having its inner end connected with the inner end of said bolt, a plate carried by the outer end of said sleeve and rotatable with said sleeve and bolt, said bolt having two indicating means thereon, a guard enclosing said plate and having an 100 opening with which one of said plate carried indicating means registers when the bolt is in locked position and with which the other indicating means registers 105 when said bolt is in unlocked position, and a second plate movable to close said guard opening only when said bolt is in unlocked position, a second plate 110 movable to close said guard opening only when said bolt is in unlocked position, and means carried by said first plate and engageable with said second plate, should the same be in position closing said opening, to move said second plate to clear the guard opening 115 upon said bolt being moved to locked position.

9. An indicating means for a door provided with a locking means, comprising a means for indicating that the door has been 120 opened and then locked from the inside, and means for indicating that the door has been unlocked from the inside.

10. An indicating means for a door provided with a locking means, comprising a 125

means for indicating that the lock has not been operated and movable by the locking means to a position to indicate that the door has been locked and movable to another position by the locking means to indicate that the door has been unlocked.

11. An indicating means, comprising a

door having a lock member, and means operated by the lock member for indicating when the door has been unlocked and then locked and then unlocked again. 10

In testimony whereof, I affix my signature.

BENJAMIN M. WEINBERGER.
